FUSE FOR AN EXPLOSIVE PROJECTILE

Karl Erik Waldemar Hjelm, Bofors, Sweden, assignor to
Aktiebolaget Bofors, Bofors, Sweden, a Swedish corporation

Application September 13, 1954, Serial No. 455,627

Claims priority, application Sweden September 25, 1953

7 Claims. (Cl. 102—71)

The present invention relates to self-arming, striker operated fuses for explosive projectiles, more particularly to self-arming, striker operated fuses which are self-detonating a predetermined period of time after having become armed.

One of the objects of the present invention is to provide a novel and improved fuse of the general type above referred to, which is reliable and accurate in operation and simpler in design than fuses of the said type as heretofore known.

Another object of the invention is to provide a novel and improved fuse of the general type above referred to which, in response to the force of inertia acting upon the projectile upon which the fuse is mounted, automatically becomes armed and initiates a timing means which in turn causes detonation of the fuse if the same is not detonated by actuation of the striker during the period of time for which the timing means is set.

Other objects, features and advantages of the invention will be pointed out hereinafter and set forth in the appended claims forming part of the application.

In the accompanying drawing a preferred embodiment of the invention is shown by way of illustration and not by way of limitation.

In the drawings:

Fig. 1 is an isometric view of a fuse according to the invention in its safety position.

Fig. 2 is a fragmentary isometric view of the timing means of the fuse.

Fig. 3 is an isometric view similar to Fig. 1 but showing the fuse in its armed position, and

Fig. 4 is an isometric view similar to Figs. 1 and 3 but showing the components of the fuse in the positions ready for self-detonation of the fuse.

Referring to the figures in detail, the fuse mechanism is housed in a conventional casing or housing formed by a cylindrical part 1 and a conical part 2. The fuse mechanism comprises control slides 3 and 4 axially displaceable, for instance in bores provided for this purpose in housing part 1. Each slide has rack teeth 5 and 6 respectively which constitute part of the timing means more clearly shown in Fig. 2. The timing means comprise a gear shaft 7 in mesh with rack 5. Shaft 7 seats a gear 9 in mesh with a gear 11 on a shaft 12. This shaft supports one component 13 of a suitable step-by-step device, the other component 14 of which is pivoted to housing part 1 by means of a pivot pin 15. The step-by-step device is exemplified by the ratchet or escape wheel 13 coacting with the pawl 14. Gear shaft 7 is engaged by a gear 16 seated upon a shaft 17 also supporting a gear 18. This gear is in engagement with a gear 19 seated upon a gear shaft 8 in mesh with rack teeth 6 of slide 4. A spring 19 disposed in alignment with slide 4 urges, when loaded, slide 4 toward the nose of the fuse under the control of the timing means. For this purpose, one end of spring 19 is anchored within housing part 1 and the other end abuts against slide 4.

The fuse mechanism further comprises a slide 21 which

2

is transversely slidable, for instance in a bore provided for this purpose in housing part 1. The length of this transverse bore is such that slide 21 may move from the position shown in Fig. 1 in heavy lines into the position shown in thin lines. A spring 22 urges slide 21 into the latter position. The slide has a transverse bore or recess which is filled with a suitable ignition charge 23. Accordingly, slide 21 is sometimes hereinafter referred to as detonator slide. The slide coacts with slide 3 which in the position of Fig. 1 retains slide 21 in the heavy line position whereas in the position of Fig. 3, slide 3 permits movement of slide 21 into the thin line position of Fig. 1 by the action of spring 22.

The fuse mechanism also comprises a striker pin 24 which is mounted axially movable in housing part 1. The end of the striker facing detonator slide 21 is preferably pointed at 25 and formed with a collar 26. The opposite end of striker pin 24 mounts a disc 27 which serves as a plunger axially displaceable in a sleeve 28. A spring 29 fitted in sleeve 28 biases the striker pin into a position in which point 25 is spaced apart from detonator slide 21.

As appears from the previous description, in the position of slide 21 as shown in Fig. 1, the charge 23 is out of alignment with striker point 25 whereas in the slide 20 position according to Fig. 3, it is in alignment with the striker point. Accordingly, the position of Fig. 1 is the safety position and the position of Fig. 3 the armed position of slide 21.

The fuse mechanism finally comprises a two-arm lever 30 pivotally mounted within housing part 1. One arm of the lever coacts with collar 26 of striker pin 24 for the purpose of actuating the striker as will be more fully explained hereinafter. The other arm of lever 30 may coact with the respective end of slide 4 which for this purpose is preferably provided with a slanted head 4'. A pin 31 serves to limit the axial movement of slide 3 toward the nose of the fuse.

The operation of a fuse as hereinbefore described, is as follows:

Let it first be assumed that all the parts of the fuse mechanism are in the positions of Fig. 1. According to this figure, slide 3 occupies its uppermost position, that is, a position closest to the nose of the fuse. Slide 3 abuts against limit pin 31. As a result, the respective end of detonator slide 21 abuts against slide 3 so that the detonator slide is locked or retained in its safety position. Slide 4 is shown in an intermediate position below the detonator slide 21.

If, through an impact or any other cause, a downward movement be imparted to striker 24 against the action of spring 29, striker point 25 will strike a wall portion of detonator slide 21 so that the fuse cannot be accidentally detonated.

Let it now be assumed that the fuse is mounted on a projectile fired and in flight. As a result, the force of inertia acting upon slides 3 and 4 will cause the same both to move backwardly relative to the nose of the fuse. The rate of the rearward movement of slides 3 and 4 relative to the fuse housing and to each other is controlled by the ratio of transmission of the gear train included in the timing means and the action of the pawl and ratchet arrangement of the timing means. When slide 3 reaches the position of Fig. 3, detonator slide 21 is released and, hence, will be moved by the action of spring 22 into the position of Fig. 3 in which the fuse is armed. In or near this position of slide 3, gear shaft 7 becomes disengaged from rack teeth 5, or in other words, slide 3 is disconnected from the timing means. The rearward movement of slide 4 compresses spring 19 as is shown in Fig. 3. When the acceleration of the projectile has decreased to an extent such that the tension of spring 19 can overcome the force of inertia which correspondingly decreases,

3
spring 19 begins to move slide 4 towards the nose of the fuse at a rate of speed controlled by the timing means.

As a result, head 4' of slide 4 begins to approach lever 30. If at any time after the fuse has been armed and before slide head 4' makes contact with lever 30, the projectile strikes a target the fuse is detonated by the resultant actuation of striker 24. However, if the striker is not actuated during the interval of time required for slide head 4' to move from the position of Fig. 3 into the position of Fig. 4, the slide head will force lever 30 into the position of Fig. 4 thereby actuating the striker and hence detonating the fuse. As is apparent from the previous description, the action of slide 4 assures that the fuse is detonated at the end of a predetermined period of time after it has become armed thereby effectively preventing that an armed projectile falls back upon the ground.

The detonation of the explosive charge of the projectile initiated by the ignition or detonation of charge 23 is effected in a conventional manner and a detailed description thereof is not essential for the understanding of the invention. It suffices to state that the ignition of the charge in the detonator slide initiates a chain reaction causing the explosion of the charge of the projectile which is also not shown.

While the invention has been described in detail with respect to a certain now preferred example and embodiment of the invention it will be understood by those skilled in the art after understanding the invention, that various changes and modifications may be made without departing from the spirit and scope of the invention, and it is intended, therefore, to cover all such changes and modifications in the appended claims.

What is claimed as new and desired to be secured by Letters Patent is:

1. A striker operated and time controlled fuse for an explosive projectile comprising, in combination, a fuse housing, a movable striker, a charge containing detonator slide coacting with the striker for setting off said charge by the striker and movable between a safety position and an armed position, a first control slide movable between a first position retaining the detonator slide in the safety position thereof and a second position releasing said detonator slide for movement into the armed position thereof, a second movable control slide, said striker and said first and second control slides being axially displaceable within said housing and said detonating slide being axially displaceable transversely thereto, the force of inertia acting upon a fuse mounted on a projectile in flight effecting an axial displacement of said first and second control slides in one direction, the axial displacement of said first control slide causing movement of the same into the second position releasing the detonator slide, striker actuating means engageable and movable by said second control slide, axial movement of the second control slide in the direction opposite to the aforesaid one direction operating said striker actuating means, means biasing the second control slide towards said opposite direction for operating the striker actuating means, and timing means controlling the rate of axial movement of the second control slide into said opposite direction whereby the striker is actuated a predetermined period of time after movement of said detonator slide into its armed position and the first control slide into said second position.

2. A fuse according to claim 1, wherein the said striker actuating means comprise lever means pivotally mounted in coacting relationship with the striker and the second

control slide, movement of said second control slide into said opposite direction effecting engagement of said second control slide with said lever means to pivot said lever means into an actuating engagement with said striker.

3. A fuse according to claim 1, wherein the said biasing means comprise compression spring means fixed at one end and engaged at the opposite end by said second control slide, said spring means being adapted to be compressed by movement of said second control slide into the direction caused by the force of inertia.

4. A striker operated and time controlled fuse for an explosive projectile comprising, in combination, a moveable striker, a charge containing detonator slide coating with the striker for setting off the charge of the striker and movable between a safety position and an armed position, a first control slide movable between a first position retaining the detonator slide in the safety position thereof and a second position releasing the said detonator slide for movement into the armed position, a second moveable control slide, the said first and second control slides being disposed for movement in one direction by the force of inertia acting upon a fuse mounted on a projectile in flight, the inertia movement of the first control slide effecting movement thereof into the position releasing the detonator slide, striker actuating means engageable and operable by a movement of the second slide in a direction opposite to the aforesaid direction, timing means coupled with said control slides and controlling the rate of movement thereof, release means releasing the first control slide from the timing means upon movement of the said slide into the position releasing the detonator slide, and means biasing the second control slide towards said opposite direction under the control of said timing means for operating said striker actuating means whereby the striker is actuated for setting off said detonator slide charge a predetermined period of time after movement of said detonator slide into its armed position.

5. A fuse according to claim 4, wherein said timing means comprise a speed limiting means and a step-by-step motion transmitting means coupling the control slides with said speed limiting means, and wherein the said release means comprise means disengaging said motion transmitting means from the first control slide in response to movement of said first control slide to a predetermined position.

6. A fuse according to claim 5, wherein said speed limiting means comprise a ratchet and pawl arrangement and said motion transmitting means comprises a gear train and rack gear teeth on each of said control slides in meshing engagement with said gear train, and said release means including a portion devoid of gear teeth immediately adjacent to the rack gear teeth of the first control slide.

7. A fuse according to claim 6, wherein release of the first control slide from the timing means is operative to free the second control slide for the aforesaid actuation by said biasing means.
